UNITED STATES PATENT OFFICE

99,571

DESIGN FOR A TEXTILE FABRIC

Curt Erwin Forstmann, Montclair, N. J.

Application October 5, 1935, Serial No. 58,857

Term of patent 14 years

To all whom it may concern:

Be it known that I, Curt Erwin Forstmann, a citizen of the United States, residing at Montclair, in the county of Essex and State of New Jersey, have invented a new, original, and ornamental Design for a Textile Fabric, of which the following is a specification, reference being had to the accompanying drawing, forming part thereof.

In the drawing, the sole figure of which is a plan view of a piece of the textile fabric embodying the design of the present invention, the cloth depicted is of a single color.

The design has a rippled appearance, comprising rough elevations arranged in groups of four along the diagonals of squares and radiating from the centers of the squares, said elevations being irregular in outline and the squares being delineated by reticulated depressed lines extending over the surface of the fabric.

I claim:

The ornamental design for a textile fabric, as shown and described.

CURT ERWIN FORSTMANN.
